ABSTRACT OF THE DISCLOSURE

An apparatus for containing a plurality of cigarettes and igniting and dispensing one cigarette at a time, including an ignition means, a timer for operating the ignition means for an appropriate time period, an actuator for starting the ignition means and the timer, and a movable drawer which when opened dispenses a lit cigarette and when closed winds the timer.

BACKGROUND OF THE INVENTION

Field of the invention

This invention relates to apparatus for containing, igniting and dispensing cigarettes, and more particularly to apparatus which, after its operation is initiated, ignites and dispenses the cigarettes automatically.

Description of the prior art

Prior art apparatus of the type described above, each generally includes a storage chamber for containing a plurality of cigarettes, an ignition means, a transport mechanism for conveying one cigarette at a time from the chamber to the ignition means and for ejecting or dispensing each lit cigarette. Alternatively the cigarettes may merely fall between locations instead of being positively moved. An apparatus having a transport mechanism is often driven by a spring or an electric rotary motor with power transmitted from the motor's drive shaft, through a gear train or cam, to the cigarette-transport mechanism. The ignition means is usually an electric heat element.

When operating properly these prior art apparatus dispense an ignited cigarette with each complete cycle or sequence of operations; however, the various structures have inherent drawbacks causing either unreliable operation or costly manufacture. With certain cigarette-transport means each cigarette is grasped and moved axially rearward for ignition, then axially forward for dispensing. This requires a substantially complex mechanism with relatively expensive components and it has been found that damaged or imperfectly formed cigarettes, which do occur, will cause jamming of such a device. Furthermore, when an electric motor is used in addition to an electric ignition means, the electric current requirement for the apparatus as a whole is often impractical.

Another prior art transport means comprises a revolving drum that carries cigarettes in grooves spaced around the drum's outer surface. This requires a rotary motor and other components for driving and regulating the drum, and it has drawbacks similar to those of the mechanism described above as regards complexity and jamming of imperfect cigarettes.

Some prior apparatus have cigarette storage chamber sub-assemblies that are rather complex in view of their purpose. Each chamber floor comprises tilting or sliding inclined plates defining between them a metered opening for releasing cigarettes to the ignition element. This has been considered an improvement over an ordinary gravity feed in which cigarettes often become jammed,

2

however, this more effective mechanism requires numerous precision moving parts.

SUMMARY OF THE INVENTION

The invention is an improved apparatus for automatically igniting and dispensing cigarettes one at a time. The apparatus housing includes a cigarette-storage chamber with a metering opening in a lower part thereof when the housing is in upright orientation. A drawer having a cigarette-carriage part is movably mounted in the housing between a first position where the carriage part is disposed below the chamber opening for receiving a cigarette therefrom, and a second position for dispensing an ignited cigarette. A switch means is provided for energizing an ignition means whereby one end of each cigarette is ignited. Also carried by the housing is a spring-actuated timer for establishing a time interval after it is started. The timer is wound when its winding lever is engaged and moved by the drawer as the drawer is moved from its second to first position. An actuator is movable on the housing between rest and third positions to thereby engage and start the timer and also close the switch means to energize the ignition means for the timer interval, the drawer being subsequently movable to second position for dispensing an ignited cigarette.

In one preferred embodiment of the new apparatus, after the operation is manually initiated, the drawer is restrained in the first position until a cigarette is ignited, and then upon release is moved automatically to the second position for dispensing the ignited cigarette. Also the ignition means comprises an electric heating element with suitable circuit components for energizing the ignition means and igniting the cigarettes. With certain changes a flame device could be substituted for the electric ignition means.

In the new apparatus' sequence of steps for a complete operation cycle, the final step is closing the drawer, after it has opened and an ignited cigarette is removed. This closing movement rewinds the timer, thus rendering the apparatus "preset" for a new cycle. Also in this new apparatus there is no requirement for any type of rotary motor to drive a cigarette transport mechanism, because the cigarettes simply fall from the storage chamber to the drawer and are then carried by the drawer as in slides to its second or open position. As will be explained more fully in the description of the preferred embodiment, this invention provides simplicity and reliability in comparison to the prior art, in addition to economy of manufacture.

BRIEF DESCRIPTION OF THE DRAWINGS

FIG. 1 is a front perspective view of the assembled apparatus of this invention prior to operation;

FIG. 2 is a similar front perspective view with the drawer in open position for dispensing a lit cigarette;

FIG. 3 is a partial front perspective and exploded view of the upper and lower housing and components therein;

FIG. 4 is a partial perspective and exploded view of the lower housing assembly and the actuator;

FIG. 5 is a rear perspective view of the actuator;

FIG. 6 is a partial top perspective view of the lower housing assembly; and

FIGS. 7 to 9 are schematic drawings of the movement of cigarettes as the drawer moves from open to closed position.

DESCRIPTION OF THE PREFERRED EMBODIMENTS

FIGS. 1 and 2 show a fully assembled preferred embodiment of the present invention in rest and actuated conditions respectively. The apparatus 10 comprises an upper housing 11, a lower housing 12, and an actuator

13. Within the upper housing is a cigarette storage chamber or hopper 14 for containing a plurality of cigarettes 15, a flue 16 associated with an ignition means, and a lock 17 to selectively prevent movement of the actuator 13. Another component is a drawer 18 which is in closed or first position in FIG. 1, and is in open position in FIG. 2 thereby dispensing a lit cigarette.

The storage chamber 14, also shown in FIG. 3, has sufficient length to accommodate the long commercial cigarettes in addition to those having standard length. The floor part 19 of this chamber is inclined downward toward the front portion 20 of the upper housing, thus providing a gravity feed structure for directing the cigarettes toward the ignition means. As further indicated in FIG. 3, the floor part 19 terminates at edge 21 leaving slot 22 through which the bottommost cigarette in the chamber may drop onto the drawer.

Other components within the housing and their interrelationship are briefly described as follows, with detailed descriptions in later paragraphs. With the apparatus in the rest condition before the operation begins as shown in FIG. 1, actuator 13 is in its rest position, drawer 18 is closed, a timer inside the housing is wound and set, one cigarette is carried by the drawer, and the ignition means is not energized. Upon depression of the actuator three separate actions occur: (a) the timer is started, (b) a switch is closed to energize the ignition means, and (c) an entrainer urges the cigarette axially until one end is closed adjacent the ignition means. The timer runs for about ten seconds, during which interval the cigarette becomes ignited. At the end of this time interval the timer releases the drawer which opens and dispenses a lit cigarette; also the ignition is de-energized and the actuator returns to its rest position. Finally, after the lit cigarette is removed from the apparatus, the drawer is slid to its closed position where it receives another cigarette, and this closing movement also winds the timer for a subsequent cycle of operation.

In continuing the detailed description, the upper and lower housings are joinable to form the final assembly, but they are shown separated in the exploded view of FIG. 3. Drawer 18 is slidably mounted on the lower housing, with its upper surface closely adjacent but not touching the lower front edge 21 of the chamber. The drawer has a front edge 23, a central part 24, two spaced tracks 25, two side parts 26 and 27, two spaced parallel grooves that are not shown but are in the bottom surfaces of the side parts and extend parallel to the upper tracks 25. Immediately adjacent each bottom groove in the drawer is a complementary groove (also not shown) in the lower housing 12, and a plurality of steel balls are disposed between each pair of complementary grooves to provide a low-friction sliding junction between the drawer and the housing.

Flat springs 28 formed into a U-shape extend from the base 29 of housing 12 into the drawer's tracks 25 which are inclined downward and rearward. The springs are biased downward into the tracks, and due to the tracks' incline, the spring force biases the drawer to move forward to its open or second position for dispensing a lit cigarette. Also shown in FIG. 3 are stop means for establishing the limits of the drawer's movement in open and closed positions. At the rear end of side 27 is hook part 30 which is engageable to stop 31 as the drawer reaches its open position. When the drawer is moved inward to its closed or first position, lower part 32 of the drawer's side part 26 has a downward extending hook part 33 that contacts the top surface 34 of latch spring 35. The spring's normal position is slightly above the floor 29 of the lower housing to which it is attached. Upon closing the drawer, hook 33 slides against the spring, maintaining it deflected downward until the hook part passes the end 36 of the spring. At that point the end 36 returns to its normal upward position and its edge engages the hook 33 and prevents the drawer from moving outward, until the spring is again depressed. The drawer is

guided in its straight line movement partially by the aligned grooves and partially by springs 28 being in tracks 25. Between each of these springs and its corresponding track is at least one steel ball to reduce friction. Of course the various steel balls could be replaced by other anti-friction components.

Near the forward end of drawer 18 is cigarette-carriage part 37. When the drawer is closed the carriage part becomes disposed below chamber metering slot 22 for receiving a cigarette from the chamber. Adjacent carriage part 37 is a clamp 38 spring-biased to pivot clockwise in the view shown in FIG. 3. Finger 39 of the clamp will descend and hold a cigarette against carriage part 37 when the drawer opens, thus preventing a lit cigarette from bouncing or falling out of the open drawer. Subsequently, when the drawer is closed, a lever part 40 of the clamp engages an edge of the lower housing, whereby the finger 39 pivots counterclockwise leaving the carriage part 37 unobstructed to receive another cigarette.

20 The actuator 13, for initiating operation of this apparatus, is shown at rest in FIG. 1 and depressed in FIG. 2. The actuator is also shown in association with the timer sub-assembly 46 in the side perspective view of FIG. 4 and in the rear perspective view of FIG. 5. The actuator 25 has a body part 41, an upper contact surface 42, a front face 43, an interior beam 44, and a resilient hook element 45 which is deflectable in a plane generally parallel to the front face 43. Rather than being mounted on the housing 11, this actuator is secured by arm 47 to the internally-mounted timer sub-assembly. Depression of the actuator 30 pivots arm 47 downward, and the arm's finger element 48 starts the timer and closes the ignition switch 64.

The timer frame is formed of upper plate 49 on which arm 47 is pivotally mounted and biased upward, and 35 lower plate 50 mounted directly to the lower housing 12. Between these plates is mounted a spring-operated escape- 40 ment mechanism, which includes a pivotable input-output member 51. From this member extend winding lever 52 and release lever 53. FIG. 4 shows in an exploded view, 45 the actuator 13 and timer 46 combination in its proper orientation, but spaced above and to the side of lower housing 12. When this combination is mounted in its assembled position, winding lever 52 would be in the path of pawl 54 extending from side part 26 of the drawer. On closing the drawer the pawl engages lever 52 and rotates member 51 until the timer becomes fully wound. 50 As the drawer fully closes the pawl is cammed by its tapered edge 54' to a horizontal orientation to provide clearance for the winding lever 52 when the timer unwinds. At a later time when the apparatus is operated and the timer unwinds, member 51 revolves clockwise as 55 shown in FIG. 5, with release lever 53 engaging and depressing latch spring 34. After the timer has run for about 10 seconds and member 51 has fully rotated, spring 34 is depressed enough to become disengaged from hook 33 of the drawer which then opens automatically due to the urging by springs 28.

For igniting the cigarettes the ignition means 55 and its associated circuit are provided, and shown most clearly in FIG. 3. Ignition element 56 is a resistance wire which becomes electrically energized during the timing interval. Adjacent structure above the element is a flue which extends through the upper housing 11 to opening 16. From element 56 copper strip 57 extends with its free end 58 closely adjacent end 59 of copper strip 60. Circuit elements 61 and 62 connect light bulb 63 between strip 60 and a terminal. For controlling this circuit there is the ignition switch means 64 comprising fixed element 65 and resilient element 66.

Associated with the ignition operation are three additional components: spacer 67, push member 69, and circuit breaker 72. The spacer is mounted on the drawer and has a loop portion 68 adjacent one end of the cigarette-carriage part 37, when the drawer is closed the loop 68 75 is closely adjacent without touching heating element 56.

The push member 69 is pivotally mounted in the upper housing 11 with its arm 70 engaged to the actuator and its resilient arm 71 extending toward the cigarette carriage 37. Depression of the actuator causes both arms to rotate counterclockwise.

The third component is a heat-actuated circuit breaker 72 comprising a bimetallic strip having one end 73 secured to the lower housing wall near copper strip 57 and its opposite end 74 engaged to and restraining slidably block 75 in a forward normal operation position, with its forward end 76 against stop 77. In this position edge 78 of the block urges the ends 58 and 59 of copper strips 57 and 60 respectively to remain in contact and thereby permit the ignition circuit to be closed. If, however, this circuit remained closed for too long a period the ignition element would overheat in addition to the fact that a considerable amount of electric current would be wastefully consumed. As shown in both FIGS. 3 and 6, end 73 of circuit breaker 72 is touching the ignition means 55. Should the element 56 overheat, bimetallic breaker 72 will deflect until its end 74 is disengaged from block 75 which then moves rearward due to a biasing means, with the result that copper strip portions 58 and 59 become separated. Upon this separation the ignition circuit is opened, as shown in FIG. 6 and later when the breaker has cooled and returned to its normal position, block 75 may be manually pushed forward to re-engage the breaker and re-engage strips 58 and 59. This protects the apparatus from overheating, which might occur if a person held the actuator depressed without permitting the apparatus to cycle normally, or if a portion of the apparatus circuit malfunctioned.

As indicated earlier, ignition of a cigarette involves a sequence of steps by different components of the apparatus shown in FIGS. 3, 4 and 5. With the apparatus 35 in its rest condition, the drawer is closed and a cigarette is disposed on the drawer's cigarette-carriage part 37. Depression of actuator 13 causes arm 48 to descend and its end part 48A to contact and depress element 66; this actuates the switch means, closes the ignition circuit and thereby energizes heating element 56. This actuator depression also causes push member 69 to rotate with a portion of its arm 71 engaging one end of a cigarette on the carriage 37 and urging the cigarette's ignitable end toward the ignition means. Spacer 67 provides numerous benefits by preventing this ignitable end from actually touching the ignition element. Such contact in the prior art often caused partial welding of the cigarette to the element and associated interference with subsequent dispensing of the cigarette; this contact has also produced a residue on ignition elements which caused undesirable smoke and impaired subsequent ignition. In the new apparatus, the period of ignition is established by the timer which runs for a predetermined interval after the actuator is depressed. At the lowest point of this depression, spring 45 on the actuator's side engages and locks onto the closed drawer. At the end of the time interval, when the timer's release lever permits the drawer to open, the spring 45 is freed, and the actuator returns to its rest position.

FIGS. 7, 8 and 9 show schematically, a subassembly of interacting components for joggling cigarettes in the storage chamber to prevent the cigarettes from jamming and failing to fall one at a time onto the drawer's carriage part 37 with each cycle. FIG. 7 shows a portion of the cigarette storage chamber comprising floor 19, floor edge 21, front wall 20 and slot 22. Below the chamber drawer 18 is in its open position with the cigarette carriage 37

shown empty. Near tracks 25 and slightly rearward of carriage 37 are bumpers 80 having top surface 81, front taper 82, and rear taper 83. Also shown are a typical drawer biasing spring 28 and cigarettes A, B and C in the storage chamber.

In FIG. 8 drawer 18 has been moved partially inward, with taper 83 contacting, rotating and joggling cigarettes B and A. FIG. 9 shows the drawer moved to its fully closed position at which time spring 28 is cammed upward by the inclined portion of track 25, and carriage part 37 becomes aligned with slot 22 whereby cigarette B falls onto the carriage. The upward motion of the spring into the area of slot 22 is abrupt and thus further joggles cigarettes it contacts directly and indirectly. When the drawer opens, these various relative positions are reversed and further joggling occurs.

What is claimed is:

1. In combination with a cigarette igniting and dispensing apparatus of the type having:

- (a) a housing with a storage chamber therein;
- (b) a drawer including a cigarette-carriage part, said drawer being movably mounted in said housing, and which drawer is capable of receiving an unlighted cigarette from said storage chamber and dispensing such cigarette after ignition;
- (c) ignition means carried by the housing for igniting one end of each cigarette;
- (d) switch means for energizing the ignition means;
- (e) a timer mounted on said housing and engageable by said drawer;
- (f) biasing means mounted on said housing to maintain said drawer in a closed position, the improvement which comprises;
- (g) said timer including a movable shaft, a winding lever protruding radially from said shaft capable of being rotated upon closing of said drawer, a spring attached to said winding lever which is stressed upon the rotation of said arm, and which spring drives said timer upon release, a release lever capable of releasing said biasing means upon release of said timer thereby causing said drawer to open;
- (h) a resilient push member mounted on said housing;
- (i) an actuator movable on said housing including a switch member which communicates with said push member such that said push member will drive said cigarette to adjacent said ignition means, and which actuator releases said spring in said timer and closes said switch means to energize said ignition means.

2. A cigarette igniting and dispensing device as recited in claim 1 further comprising a clamp pivotally mounted on the drawer, the clamp having a finger adjacent the carriage part and being biased to pivot whereby the finger bears against a cigarette on said carriage part when said drawer is moved to its open position.
